(57) CLAIM

We claim the ornamental design for a beam for a partition assembly, as shown.

DESCRIPTION

FIG. 1 is a perspective view showing a front, top and first end of the beam for a partition assembly of the present invention; FIG. 2 is an enlarged fragmented perspective view of the front, top and first end of the beam for a partition assembly shown in FIG. 1.

FIG. 3 is a front elevational view of the beam for a partition assembly, the rear elevational view being a mirror image thereof;

FIG. 4 is an elevational view of the first end of the beam for a partition assembly, the opposite and second end view being a mirror image thereof;

FIG. 5 is a top plan view of the beam for a partition assembly; FIG. 6 is a bottom plan view of the beam for a partition assembly; and,

FIG. 7 is an enlarged fragmented bottom plan view of the beam for a partition assembly shown in FIG. 6.

Broken lines in the drawings form no part of the design as claimed.
